SPACE HEATER

Bernard P. Lunkwicz, Dallas, Tex., assignor to Dearborn
Stove Company, Dallas, Tex., a company of Texas

Application November 23, 1956, Serial No. 43,918

Term of patent 14 years

(Cl. D81—10)

I claim:

The ornamental design for a space heater, substantially as shown.
